AUTOMATICALLY THREADING LOOM
SHUTTLE

William L. McHargue, Fairfax, Ala., assignor to
West Point Manufacturing Company, Shaw-
mut, Ala., a corporation of Alabama

Application April 10, 1951, Serial No. 220,264

4 Claims. (Cl. 139—223)

1

This invention relates to shuttles for use in weft replenishing looms and relates more particularly to a self-threading shuttle having an improved eye block construction.

Self-threading shuttles are well known in the art, and many different threading blocks or eye blocks, as they are sometimes referred to, have been developed for use with such shuttles to provide a threading block which accomplishes easy threading and, at the same time, does not allow the filling thread to become unthreaded from the threading eye until the bobbin of thread is used up and the empty bobbin has been discharged from its position within the shuttle.

One of the defects in threading eye blocks of the prior art resides in the fact that the filling thread often becomes displaced from its passageway within the threading eye, which often causes the premature discharge of the bobbin from the shuttle prior to the filling thread therein being exhausted.

Some of the improved threading blocks developed for use with the self-threading type shuttle have been fairly successful in overcoming the above mentioned problems, but most of these have been complicated and costly to manufacture, or for other reasons have not proven otherwise satisfactory.

With modern day high speed looms, a threading eye or block is needed which is simple of construction and efficient in operation and, at the same time, does not require an excessive number of picks to complete threading through the filling thread passageways within the threading eye.

According to the present invention, I have developed an improved threading eye or block which is simple of construction and very efficient in operation.

One object, therefore, of the present invention is to provide a shuttle of the self-threading type which may be satisfactorily used with different type yarns.

A further object is to provide an improved shuttle eye block of the self-threading type having a wear resistant delivery eye so designed as to permit easy threading, but which retains the yarn, so that the yarn cannot escape forwardly from the block during the weaving operation.

A further object is to provide a shuttle eye block with means for preventing the yarn from escaping by ballooning and also from escaping by spinning in a forward direction from the delivery eye.

A still further object is to provide a shuttle 55 threading block of simple, durable and inex-

2

pensive construction and so designed as to prevent accidental escape of the yarn from its threaded course between the bobbin tip and the eye.

5 Other and further objects and advantages of the invention will become more apparent following the detailed description and with reference to the accompanying drawings wherein:

Figure 1 is a top plan view of a conventional weaving shuttle having the eye or threading block of the present invention embodied therein;

Figure 2 is a side view showing the threading block in position;

Figure 3 is an end view of the threading block 15 taken through the line 3—3 of Figure 2; and

Figure 4 is a similar view of the opposite end taken through the line 4—4 of Figure 2.

Referring to the drawings in more detail wherein like numerals indicate like parts in the 20 different views, Figure 1 shows a conventional weaving shuttle 6 having the filling carrier opening 8 with a filled bobbin 10 disposed thereon and a second opening 9 to receive the novel shuttle eye threading block of the present invention.

25 This arrangement of parts is of conventional construction.

The improved shuttle eye threading block, generally indicated at 12, may be made of any of the usual materials, for example, brass or bronze, and 30 by any usual operation, such as die casting, and is shaped to fit into the threading chamber provided for its reception in the forward part of the shuttle body. As illustrated in Figures 3 and 4, the block has a transverse bore 14 to receive the bolt 16 by means of which the block is 35 secured in place in the shuttle body.

The novel threading eye block which I have 40 invented comprises a main or body portion 18 (Fig. 1) which is composed of the lower portion

45 19 (Fig. 3) and the top guide 11, which is integral with the lower portion on one side but terminates short of contact on the other side to define an elongated narrow inlet 20. The inlet 20 opens into a thread passage 22 (Fig. 3) within the body portion. The top guide 11 has a rounded smooth surface 21 on the portion facing the inlet 20 so as to cause the filling thread to be directed to the thread passage 22. The lower portion 19 and the top guide 11 are dished at the end facing the filling carrier as seen at 24. The lower body portion 19 is also dished slightly at its 50 opposite end as seen at 26, since the filling thread bears against this surface as it passes through the second thread passage. The top guide 11 has a cut out portion 23 in the end opposite from fill-

ing carrier 18 which forms the hook 25. This end of the top guide is of slightly less width than the bottom portion 19 so as to give a slightly coned configuration to the interior thread passage 22.

The top guide 11 acts to direct the thread to passage 22, and the hook 25 aids in retaining the thread in passage 22 when threaded and also provides a surface against which the filling thread may be discharged in case the filling thread does not pass beneath horn 30 during the first several picks.

Integral with the main body portion 18 is the offset portion 28 from which the horn member 30 extends. The horn 30 is rounded on its upper surface and extends in a slightly curved path from the offset portion 28 with its tip portion 32 terminating adjacent the cut-away side portion 34 of the shuttle. The body portion, offset portion, and horn member are all seated in the openings 9 and 44 which are cut out in the shuttle so as to form complementary seats for these parts. Depending from beneath horn 30 is the finger or claw member 36 (Fig. 4) which has two forked hook members 38 and 40 integral therewith. The hooks 38 and 40 are curved downwardly and inwardly from the horn 30 and terminate adjacent the lower section 19 of the body portion 18. The two hook members are angularly disposed relative to each other so as to define a second thread passage 41 which intersects the first passage substantially at right angles.

The under face of the horn 30 is cut away as seen at 42 (Fig. 2) so as to provide an inclined surface to lead the thread into the thread passages and out through the side delivery opening 44 in the side of the shuttle 6. The offset portion 28 is slightly dished at the point 37 just below where the horn 30 is joined to form a third thread passage 51 and also to provide a contact surface for the filling thread as the shuttle moves toward the right across the loom.

In operation the threading block of the present invention works as follows. When a new thread carrier is inserted in the recess within the shuttle body, the leading edge of the thread from the bobbin will be held at the side of the loom, while the shuttle makes its first pick. During the first pick thread 46 will be moved under the tip 32 of the horn 30 in which position it will be carried until the second pick is commenced, which pulls the filling thread 46 in the opposite direction causing the filling thread to slide rapidly down the inclined smooth undersurface 42 of horn 30 and over the top of the smooth curved surface of finger 36 at which point the thread 46 is pulled beneath the hook or claw members 38 and 40. The tip 32 of horn 30 acts as a thread directing means. As previously pointed out, the undersurface 42 of horn 30 is shaped so as to lead the thread 46 out through the side delivery opening 44 in contact with the dished portion 37 of the offset portion 28. When the third pick is commenced, the pull on filling thread 46 will be reversed causing the thread to ride against the metal pin or post 48 which is vertically secured forwardly of the side delivery passage. The filling thread 46 will be completely threaded through the passages of the threading eye or block 12 as shown in Figures 1 and 2 at this point.

It will be noted that by this arrangement a series of thread passages is provided leading from the body portion facing the carrier opening to lead the filling thread to the side delivery eye in the shuttle.

No contact post is needed on the reverse stroke

75

of the shuttle, since the thread rides in groove 37 of the offset portion 28 from which horn 30 extends.

When in its fully threaded condition, which may be accomplished in two picks, no amount of ballooning or movement of the thread 46 will effect its removal from the thread passages of the threading block of the present invention. The hooks 38 and 40 are angularly disposed relative to each other and as has been pointed out are curved around the second thread passageway. These hook members are so disposed relative to each other and relative to the second thread passageway that even if filling thread 46 should escape from beneath one of these hooks, it would bear against the other hook and would not be removed from this passageway.

Hooks 38 and 40 are rounded and smooth, as are all of the other surfaces of my improved device which come in contact with the filling thread. This prevents unnecessary breakage resulting from the friction of the threads with the threading eye. This is of particular importance if the filling thread should become displaced from one or more of the passageways whereby any slightly sharpened surface would cause breakage with consequent stoppage of the loom under the high speed running conditions employed today.

The horn 30 has the tip portion 32 so shaped as to make the accidental displacement of thread 46 almost impossible even if the thread should escape from beneath hooks 38 and 40. As has been pointed out, the under side of horn 30 is designed so as to lead the thread down, over and around finger 36 and hooks 38 and 40, and when in this position to provide a channel or passageway leading the thread out of the side delivery opening cut in the side of the shuttle body.

By means of this arrangement of parts a shuttle eye threading block is provided which is simply constructed and which is extremely efficient and reliable in operation representing a decided improvement over devices of this nature heretofore used.

I claim:

1. In an automatically threading shuttle having an opening to accommodate a filling carrier, an automatic threading block disposed forwardly of said filling carrier and having means to direct the filling thread to a series of thread passages within said block as the shuttle is moved across the loom, means on said block to prevent unthreading once the filling thread has been positioned within said block, said means comprising a horn member integral with and extending forwardly of said block, a curved finger member depending from said horn member, an inturned hook on said finger terminating short of contact with the forward portion of said block, a second inturned hook on said finger angularly disposed relative to said first hook, said finger member defining a thread passage leading to a side delivery opening in said shuttle with said hooks acting to prevent displacement of the thread from said passage when in threaded position.

2. In an automatically threading shuttle having an opening to accommodate a filling carrier, an automatic threading block secured in one end of said shuttle, thread passages through said block, a horn to direct the thread into said passages as the shuttle moves across the loom, and a plurality of hook members on said horn and depending downwardly and inwardly therefrom toward said block to prevent accidental

displacement of the thread from said thread passages.

3. In an automatically threading shuttle having an opening to accommodate a filling carrier, an automatic threading block secured in one end of said shuttle, said block comprising a body portion having a substantially longitudinal thread passage therethrough, one side of said body having a longitudinally extending transverse inlet communicating with said thread passage, said body portion being dished at both ends thereof, a second thread receiving passage communicating with said first passage to lead said thread to a side delivery opening in said shuttle, a horn member protruding from said body portion to direct said thread into said thread passages, and a series of hook members on said horn adjacent to and angularly disposed relative to each other to prevent said thread from accidental unthreading from said block when in threaded position.

4. A threader for automatically threading loom shuttles, said threader having a main body portion with a longitudinally extending thread passage therethrough, a thread directing top guide on said body portion disposed above said passage, a longitudinally extending opening positioned below said guide in said body portion

and communicating with said thread passage, a thread directing horn member extending in a curved path forwardly of said body portion to direct the thread to said top guide, a curved finger member extending obliquely from said horn, inturned hook members integral with said finger so as to define a second thread passage leading from said first thread passage, said hook members being angularly disposed to each other to constitute thread retaining guards surrounding said second thread passage, and an inclined surface on the bottom side of said horn to lead the thread from said second passage to a side delivery opening in the shuttle.

WILLIAM L. McHARGUE.
